UNITED STATES PATENT OFFICE

SAM A. THREEFOOT, OF MERIDIAN, MISSISSIPPI

CARD TABLE

Application filed September 16, 1932. Serial No. 633,435.

This invention relates to tables which are primarily designed for use in playing cards, and more particularly for use in playing the game known as "contract bridge."

In playing a game of contract bridge it is particularly desirable for each player to know the state of the score of games, and to this end it is customary for each of the four players to have a separate score pad and to keep the score in duplicate with the others.

The object of my invention is to provide a form of card table which will avoid the necessity for each player to keep the score on a separate pad, so that the score may be kept on a single pad, which, after the entry of the score, may be placed in a position in which all the players may readily inspect it at the same time, and in which position it will not interfere with the use of the table for the purposes for which it is primarily intended.

I accomplish this object by providing the table with a score-pad-holding tray which is mounted in the table below its top surface and is movable from points at one side of the middle of one edge of the table to the middle thereof, so that, when the tray is in its innermost position, the pad will be held in the middle of the table beneath a window with which the table is fitted, in which position it may be readily inspected by all the players.

For a more complete disclosure of the invention reference is now made to the following specification in connection with the accompanying drawing, in which:

Fig. 1 is a plan view of the top side of a card table embodying my invention.

Fig. 2 is an edge view thereof and

Figs. 3 and 4 are sectional views on the lines 3—3 and 4—4, respectively of Fig. 1.

In the drawing a card table *a*, of the usual square formation, is indicated, having legs *b* at each corner.

According to my invention, I provide a flat tray *c* which is slidably mounted in suitable guideways *d* supported on the under side of the table top, said guideways being arranged to extend from one of the edges of the table, at the right hand side of the middle thereof, obliquely to corresponding points at the opposite edge, so that the tray will be

guided to slide beneath the middle portion of the table, as it is moved obliquely from right to left. Said tray is provided with a score-pad receiving recess *e* which is preferably of square formation and is adapted to receive a common form of score pad *f*. A square opening *a'* is formed in the table top, the sides of which are equidistant from and parallel to the corresponding side edges of the table top, so that the opening will be centrally located therein and a glass plate *g* is set into, and closely fitted at its edges to said opening with its top surface flush with the top surface of the table, so that no break, or irregularity is formed therein, and the pad-receiving recess in the tray is so arranged that when the tray is in its innermost position it will be directly beneath and in register with glass *g*, as shown in Figs. 1, 3 and 4. The tray may also have a pencil receiving recess *h*.

In use, when the score is to be recorded, the tray will be drawn out to the dotted line position of Fig. 1 and the score will be entered on the pad *f* by the player who sits at that side of the table, and then the tray will be pushed in to the full line position of Fig. 1, in which position the pad will be held directly beneath the glass plate *g*, so that the figures which have been entered may be readily seen by the other players during the progress of the bidding on the next hand.

The construction in no way interferes with the playing of the cards, the necessity of having one or more pads on the top of the table is avoided and the score may be conveniently entered on the pad when the play is finished, a single score thus serving for all the players.

I claim:

A card table of square formation having a score pad opening in the middle thereof and a transparent closure plate for said opening having its top surface flush with the top surface of the table, and a rectangular score-pad-holding tray slidably mounted in the table beneath its top surface and slidably obliquely to said opening from one side of the middle of one edge of the table beneath said opening, to position the pad directly beneath

said closure plate when the tray is in its innermost position and to permit the pad to be held beyond said edge when the tray is withdrawn in a position parallel to that under
5 the opening.

In testimony whereof, I have signed my name to this specification.

SAM A. THREEFOOT.
